UNITED STATES PATENT OFFICE.

EDWARD BROWN, OF PHILADELPHIA, PENNSYLVANIA.

IMPROVEMENT IN VALVE-GEAR FOR STEAM-ENGINES.

Specification forming part of Letters Patent No. 44,071, dated September 6, 1864.

To all whom it may concern:

Be it known that I, EDWARD BROWN, of Philadelphia, county of Philadelphia, and State of Pennsylvania, have invented a new and Improved Mode of Operating the Slide-Valves of Steam-Engines; and I do hereby declare that the following is a full, clear, and exact description thereof, reference being had to the annexed drawings, making part of this specification, and to the letters of reference marked thereon.

The same letters in different figures refer to the same parts.

Figure 1 is a plan. Fig. 2 is a side elevation. Fig. 3 is a side view of grooved disk. Fig. 4 is an end view of carrying-arm. Fig. 5 is a side view of fixed flange.

The nature of my invention consists in operating the slide-valve of a steam-engine by means of a grooved disk fitted on the main shaft of the engine and capable of being fixed in any required position or angle, and a common eccentric, the rods from which eccentric and disk are connected to a link or lever which works the valve-stem of the engine. The commonest kind of steam-engine is the three port slide-valve, the valve of which is generally operated by means of an eccentric or by two eccentrics connected by a slotted link. The motion communicated by this means is very defective in cutting off the steam at an early point of the stroke. In fact, it will not cut off much earlier than half stroke without giving a very small port. The motion at the point of cut off is very slow, and the compression and exhaust are too early, thus neutralizing the advantage of cutting off the steam short.

By my mode of operating the slide-valve the port is larger, the cut-off much more rapid, (an essential point,) while the lead-points of compression and exhaust remain the same when cutting off at one-sixth as at three-quarters of the stroke.

I will now describe the parts:

In Fig. 1, D is the main shaft of the engine. A is the grooved disk. It is bored to fit the main shaft of the engine. B is a flange fitted and keyed fast on shaft D, and to which the disk A is bolted by the bolt e in any position that may be required. This flange B has a curved slot in it, as shown at f, Fig. 5, in which the bolt e works laterally

when the disk A is moved round the shaft. C is a common eccentric keyed fast on the shaft D, and connected to one end, S, of lever R by means of a rod, Q. F represents the crank of the engine, and g the crank-pin. The disk A has a groove cast in its side, as shown in Fig. 3. The groove in this disk is formed by two curves, H and I, concentric with the center of shaft D, but at different distances from the center. These curves are joined by the grooves J and K, forming inclined planes. In this groove runs a roller, L. (See Fig. 4). It turns on a pin, n, fixed in the carrying-arm m. This arm m vibrates on the pin o, fixed to the framing of the engine. To it is also fixed, by a pin, p, the connecting-arm Q', which is attached at its opposite end to one end, S', of the lever R, which said lever R is connected at its center r' to the valve-stem T.

In Fig. 2 the diagram w v x y shows the position of the crank in relation to that of the valve Z, at the point of cut-off—viz., four and a half inches out of a twelve inch stroke. The circle x y represents the path of the crank-pin, and the straight line w v, that of the piston; the figures 1 2 3, &c., on the line w v, which the piston may be supposed to reach successively, at the same time that the crank-pin g reaches the points 1 2 3, &c., on the circle x. The crank travels in the direction of arrow d'. The ports a' and a'' lead to opposite ends of the cylinder.

The operation of my valve-motion is as follows: The crank being placed on its dead-center o, Fig. 2, the valve Z will be just admitting steam at the port a''. The eccentric C is keyed fast on the shaft D at about one hundred and twenty degrees in advance of the crank. As the crank moves toward position F, the valve Z is opened by the eccentric, and admits steam to the cylinder. The disk A is fixed to the flange B in such a position or angle so that the inclined part K of the groove strikes the roller L and communicates its motion to the valve-stem T just at the time it is wanted to cut off the steam, which will generally be from one-third to one-half of the stroke. The eccentric at this time is near the end of its throw, and consequently giving very little motion to the valve Z. The action of the incline K, coming against the roller L at this time, gives a very rapid motion to the valve,

shutting off steam at about four and one-half inches, as shown in Fig. 2, the crank being in position F. The disk A having performed its office of cutting off the steam, the arm *m* remains stationary until the crank has made half a revolution, when the incline J comes into operation with the roller L and again cuts off steam at the return-stroke of the piston. Thus the valve Z receives its motion from the eccentric C, except when it is near the extremity of each stroke, and then the inclines J and K come into operation and perform the cut-off.

By turning the disk A forward or backward on the shaft D and securing it fast to flange B, the inclines J and K are brought so much earlier or later in contact with roller L, thus shortening or lengthening the period of cut-off. Instead of the disk A being turned round by hand and set fast by flange B, it may be made movable by a screw fixed to disk A and a rack cast on flange B; or it may be moved by means of a spiral feather on the shaft D, both methods being well known for turning eccentrics upon a shaft; or, instead of turning the disk A upon the shaft, the point of cut-off may be altered by raising or lowering the roller L in the groove H I by means of a lever, C', as shown in Fig. 6, and if the go-

ernor of the engine be attached to handle C'' the cut-off is then variable by the governor. A three-cornered cam, as shown, Fig. 7, will partially answer the same as disk A; but its motion in cutting off steam is not so rapid as disk A. This valve-motion may be applied to the valve-stem of three-port slide-valves, plate or piston valves, or two-port slide-valves at each end of the cylinder, or balanced slide-valves.

I do not claim the use of a single eccentric and cam connected by rods to a link or lever for operating the slide-valve; but

What I claim as my invention, and desire to secure by Letters Patent, is—

1. Operating the slide-valve of a steam-engine by means of a single eccentric, C, and a cam or grooved disk, A, when the said grooved disk is shaped as described, and the point of cut-off varied by turning the said cam on the shaft, substantially as described.

2. The combination of the eccentric C, disk A, flange B, roller L, arm *m*, rods Q Q', and lever R, arranged and operating substantially as described.

EDWARD BROWN.
